UNITED STATES PATENT OFFICE.

CHRISTOPHER JOHN MONTGOMERY, OF LIVERPOOL, ENGLAND.

MACHINE FOR MAKING BARREL-HEADS.

1,377,968.

Specification of Letters Patent. Patented May 10, 1921.

Application filed November 9, 1920. Serial No. 422,912.

To all whom it may concern:

Be it known that I, CHRISTOPHER JOHN MONTGOMERY, a subject of the King of England, and residing at Grassendale, Liverpool, in the county of Lancaster, England, have invented Improvements in and Connected with Machines for Making Barrel-Heads, of which the following is a specification.

This invention has reference to the manufacture by machinery of wooden barrel-heads, or like disks, or articles, but for convenience of description it will be described as applied to the manufacture of barrel-heads. One of the objects and effects of the invention is to enable barrel-heads or like articles to be made rapidly and inexpensively, which at the same time are accurate and true.

The operation on the barrel-head to be performed in this machine is that of finishing off, or particularly beveling, the edges of the ends or heads which are to fit in the grooves provided on the inside of the ends of the staves of the barrels, and making them of the form of the figure of revolution required.

In the making and finishing off of the ends or heads they are made of polygonal form roughly approximating a circle, and then a multiplicity of them so formed are piled together and supported in this arrangement in a machine, and slowly revolved past a multiplicity of revolving cutters so that the edges of the ends are gradually cut and shaped; say beveled, all around and to the true form required, either circular or elliptical. The revolving cutters are mechanically moved or adjusted up to and in relation to the work, being carried on common carrier parts whose movements are mechanically effected, and also in some cases mechanically controlled, which in the case of elliptical or like forms of ends or heads being made, is effected by a cam or like device which causes the cutters to be moved nearer to and farther from the work as is required, so that the cam gear and cutters move together.

A construction and arrangement of machine according to this invention is illustrated in the annexed drawings, and the invention will be further described with the aid of same.

In this drawing, Figure 1 is a side eleva-

tion of the machine, Fig. 2 is an end view, and Fig. 3 a plan.

In the machine, 1 is the lower supporting face plate on which a multiplicity of the rough heads are piled, and 2 is the upper clamping disk which is moved on to the pile of heads and off same, by a screw 3, screwing through the boss of an overhanging headstock 4, fixed on the main frame 5 of the machine. 6 are the multiplicity of cutters on each side of the machine, mounted on shafts 7 carried in swinging arms 8, fixed on the upper and lower ends of shafts 9, carried in the bracket bearings 10 of the machine frame 5.

The headstock 4 enables the whole batch of heads to be pressed firmly on to the rotary carrier face plate 1 below; and as this face plate is revolved, the batch of heads is revolved slowly by the frictional contact between them. A ball bearing 3^x is provided between the screw 3, and the face plate 2 to diminish friction of the bearing of the disk 2.

The carrier driving face plate 1 is mounted on a vertical shaft 15 mounted in the bed or pedestal 16 of the frame, and is driven from a worm wheel 17 on the shaft 15, which is operated from a worm 18 (see Fig. 1), and driving gear consisting of a shaft 19 and belt wheel 20 thereon, which is driven from the belt gearing hereinafter described.

The face plate 1 also serves as a cam which is adapted to operate the cutter carrier parts through levers or arms; namely, the plate 1 is provided with a cam shaped channel 21 on its underside, and in this channel, a roller 22 on the end of each of the arms 23, loosely mounted on the lower ends of the shafts 9, works, so that by the non-centric or cam channel, these arms will be moved toward or away from the axis of the plate 1, and move by means as hereinafter described the cutters toward and away from the axis of the plate 1, and the barrel heads to produce a slightly elliptical form of head required, when such form is required. This inward and outward movement and the rotation of the barrel heads, is a slow one.

The lower ends of the cutter carrier shafts 7, are each provided with fixed belt pulley 25, and the shafts 9 are fitted with a loosely mounted pulley 26; and the driving belts 27

which drive the shaft 7 and cutters, pass from the pulleys 28 on the prime motion shaft 29, over the pulleys 26, which serve as guides to the belts 27, and keep the required tension on the portions which extend between 26 and 25, as the cutters are rocked about the shafts 9.

The cutters 6 are threaded on their spindles 7, and may be adjusted lengthwise on same by means of lock nuts or equivalent devices.

Motion from the shaft 29 is carried to the belt gear wheels 30 by a belt 31, and thence to the shaft 19 by belts 32, this gear constituting a reversing gear adapted to be reversed by an ordinary belt fork shifting device 33.

The reversing belt shifting gear 33 is worked from a hand wheel device 35, and chain 36, and a sprocket wheel 37 supported in the bracket 38, the hub of which is a nut through which the threaded end of the shifter shaft 33 screws.

The cutter shafts 7 and their carrier arms 8 are moved up to and away from the barrel heads by a swivel nut 39 mounted in each of the lower arms 8—see Fig. 3—and a right and left hand threaded shaft 40 passing through these nuts, and operated by hand wheel 41 outside. The shaft 40 is split at the center at 40°, and the two parts are coupled together by a sleeve coupling 44 and key and feather arrangement, so that when desired, viz., when making elliptical heads, the movement of the two parts of the shaft toward and away from each other, is permitted; and the two parts of the shaft 40 are connected to the cam levers 23 by links 42 connected to shackles 43 loosely mounted between collars on the shaft 40, and thus these cam levers 23, are connected to the carrier arms 8, which are operated thereby.

When the heads are to be circular, the cam channel 21 will be circular, and the cutters will only be moved toward and away from the edges of the head by rotating the shaft 40 by the hand wheel 41; but when the heads are to be elliptical, and an elliptical cam is used, the movement of the cutters will be a compound one, viz., that produced by the cam by the means described, and that produced by the operation of the hand wheel 41.

The polygon marked 45 in Fig. 3 represents a head before it is cut and trimmed, and it consists as shown of a center board 46, two end boards 47, and two intermediate boards 48, the center board 46 being sawn square across the ends, the intermediate parts 48 being sawn by an angle, and the edge boards 47 being also sawn at an angle; thus very little waste is made.

When making the heads in the form of a circle, the wood pieces 46, 47, and 48 should

be compressed previously to cutting and finishing, in order that after they are placed in the barrels, and the hoops tightened, they will not be deformed or squeezed in, but retain the true circular form.

When an ellipse form of head or end is required to be made, the cam of the driving face plate above described, for adjusting or moving the cutters and their carrying arms is also an ellipse; but the difference between the lengths of the major and minor axes of the ellipse is quite small—say about half an inch in most cases. By the means and mechanism above described, the cutters will follow the ellipse form of the cam, but the size of the ellipse will be regulated by the hand wheel 41.

When the machine is started the heads or ends revolve very slowly, and the two cutter carrying spindles revolve at a high speed; and by operating the hand wheel 41 the cutters are gradually brought on to the edges of the heads.

The cutters may be adapted to operate on both sides of the edges of the heads at once, or by different operations, so as to produce the beveled form of edge required.

In some cases the heads, when placed in the machine, for being operated upon, will have a small strip of wood say $\frac{1}{4}$ " thick on opposite edges, so that they form distance pieces between the adjacent heads; and this is especially useful in a case where the side portions 47 are made thinner than the other boards, as they sometimes are. These distance or make-up pieces may be faced with rough sand paper or the like to produce a good friction grip between one head and the other next it, so as to insure the whole revolving together.

Moreover by the heads being separated in this manner, the cutters can be separated from one another in the manner shown in the drawings.

The machine is suitable for making heads of different sizes, and of different shapes as stated; and the cutter feed may be automatic, or hand operated; the cutting speed being altered as desired, for different timbers. The cutters may be of different shapes as may be desired, suitable means being provided for changing them.

What is claimed is:—

1. A machine for shaping and dressing the peripheral edges of barrel heads, comprising a rotary support adapted to receive a series of barrel heads arranged in superimposed relation, upright shafts mounted beyond the support, spaced cutter carrying arms mounted on each of said shafts, a cutter shaft mounted in the free ends of each set of arms, an adjusting arm mounted for free rotary movement on each of the first mentioned shafts, a connection between each of said adjusting arms, a cam way

formed in the support, a screw shaft having threaded connection with each of said cutter carrying arms, means for connecting the ends of such shafts to permit the shafts 5 to move longitudinally with respect to each other, and a connection between each of said shafts and the adjacent adjusting arm, whereby the cam way determines the cutting path of the cutters and the screw shafts 10 the dimensions of such path.

2. A machine for shaping and dressing the peripheral edges of barrel heads, comprising a rotary support formed in its under surface with a cam way, a clamping member 15 mounted above the support and adjustable with relation to the support, said clamp member being mounted for free rotation to permit the clamping of a series of barrel heads between said support 20 and clamping member, an upright shaft

mounted at each side of and in rear of the rotary support, cutter supporting arms mounted in spaced relation on said shafts, a cutter shaft mounted in the free ends of each pair of arms, an adjusting arm mounted 25 for free rotation on each upright shaft and having a roller terminal to engage in said cam way, manual operable means connected to each of said adjusting arms for simultaneously adjusting the cutter supporting arms of the respective sets in relatively opposite directions.

In testimony whereof I have signed my name to this specification in the presence of two subscribing witnesses.

CHRISTOPHER JOHN MONTGOMERY.
